UNITED STATES PATENT OFFICE.

CHARLES J. TRAVERS, OF CHICAGO, ILLINOIS, ASSIGNOR TO ROYAL METAL MANUFACTURING COMPANY, OF CHICAGO, ILLINOIS, A CORPORATION OF ILLINOIS.

DESIGN FOR A CASSEROLE-HOLDER.

43,915.

Specification for Design.

Patented Apr. 22, 1913.

Application filed June 8, 1912. Serial No. 702,571. Term of patent 3½ years.

To all whom it may concern:

Be it known that I, CHARLES J. TRAVERS, a citizen of the United States, residing at Chicago, county of Cook, and State of Illinois, have invented a new, original, and ornamental Design for Casserole-Holders, of which the following is a specification, reference being had to the accompanying drawing, forming a part thereof.

Figure 1 of the drawing is a side elevation of a casserole holder showing my new design, and Fig. 2 is a plan view thereof.

I claim:

The ornamental design for a casserole holder, as shown.

CHARLES J. TRAVERS.
